(57) **CLAIM**

The ornamental design for a display screen or portion thereof with animated graphical user interface, as shown and described.

DESCRIPTION

FIG. 1 is a front view of a first image in a sequence for a display screen or portion thereof with animated graphical user interface showing a first embodiment of the new design; FIG. 2 is a second image thereof; FIG. 3 is a third image thereof;

FIG. 4 is a front view of a first image in a sequence for a display screen or portion thereof with animated graphical user interface showing a second embodiment of the new design;

FIG. 5 is a second image thereof;

FIG. 6 is a third image thereof;

FIG. 7 is a front view of a first image in a sequence for a display screen or portion thereof with animated graphical user interface showing a third embodiment of the new design;

FIG. 8 is a second image thereof; and,

FIG. 9 is a third image thereof.

The outermost broken lines in the figures show a display screen or portion thereof, and form no part of the claimed design. The other broken lines in the figures show portions of the graphical user interface that form no part of the claimed design.

The appearance of the animated image sequentially transitions between the images shown in FIGS. 1-3, between the images shown in FIGS. 4-6 and between the images shown in FIGS. 7-9. The process or period in which one image transitions to another forms no part of the claimed design. FIGS. 2, 5 and 8 are illustrated to show contrasting appearance. Areas of the display screen or portion thereof with a graphical user interface that appear in different shades of gray represent areas with contrasting appearances.

1 Claim, 9 Drawing Sheets
